UNITED STATES PATENT OFFICE

JOHN SQUIRES, OF DETROIT, MICHIGAN

PROPELLER

Application filed March 8, 1929. Serial No. 345,304.

This invention relates to propellers and particularly to air craft propellers.

In the manufacture of such propellers it is desirable to form the blades separately, since they may individually be more conveniently handled and more readily fashioned to the desired form, than when they are integrated. In assembling the blades and hub it is also desirable to establish the same pitch relation of the blades to the plane of rotation, so that the reactions of blades may be balanced, and undue stresses and vibration avoided.

It is one object of the invention to separately form the blades of a propeller and to so connect said blades to the propeller hub as to very strongly resist such centrifugal stresses as arise in use.

Another object is to adapt propeller blades, upon their initial mounting upon the propeller hub to be rotatively adjusted on the hub, about the longitudinal axes of said propellers, and to provide complementary indicia upon the blade shanks and upon the hub to accurately indicate a desired uniformity of such rotative adjustment so as to definitely assure the same pitch relation between all of said blades and the plane of rotation of the propeller.

A further object is to adapt the blades to be accurately adjusted to and from the axis of the hub to equalize their effective distances from said axis.

Still another object is to engage the propeller blade shanks in sockets upon the hub, to provide for the aforementioned adjustments of said shanks in said sockets, and to adapt said sockets to be finally contractively clamped upon said shanks.

These and various other objects the invention attains by the construction hereinafter described and illustrated in the accompanying drawing, wherein;

Fig. 1 is a partially broken side view of the central portion of a propeller embodying the invention, sectionally showing the connection of one of the blade shanks to the hub.

Fig. 2 is a rear view of said portion, appearing as indicated at 2-2 in Figure 1.

Fig. 3 is a cross sectional view taken upon the line 3-3 of Figure 1.

Fig. 4 is a cross section on line 4-4 of Figure 1.

Fig. 5 is a fragmentary radial section 55 through one wall of one of the blade receiving sockets, showing a blade shank engaging said wall, modified somewhat from the showing of Figure 1.

In these views, the reference character 1 designates the shaft-engaging sleeve of a propeller hub, said sleeve being formed in its opening with suitable key ways 2. A pair of sockets are carried by said sleeve in diametrically opposed relation, each comprising 65 halves 3 and 4 meeting in a plane preferably transverse to the sleeve 1. The halves 3 are formed as integral projections upon said sleeve and the halves 4 are secured to said projections by two rows of bolts 5. A slight 70 clearance, indicated at 6 is left between the halves at one side of each socket so that a clamping effect may be exercised by the bolts 5 extending across such clearance (see Fig. 3).

The shanks 7 of the propeller blades are tubular, and so engaged with the hub sockets as to provide for an accurate positioning of said blades as regards the spacing of their shanks from the hub axis and as regards the angular positions of said shanks in the sockets.

To accurately regulate the spacing of the shanks 7 from the hub axis, an exteriorly screw-threaded sectional collar 8, preferably comprising complementary halves, is rotative upon each shank and is adapted, after suitable adjustment of the shank to be clamped upon the latter within the corresponding socket 3, 4. To accommodate said collars, the shanks 7 are annularly channeled, as indicated at 9, the end walls of said channels being curved gradually outward and the collar extremities being correspondingly interiorly curved. The screw threads of each collar engage interior screw threads of the corresponding socket 3, 4, as appears at 10 (Figure 1), so that a rotation of the collar, (in advance of fully tightening the bolts 5) will advance the shank toward or withdraw

it from the hub axis. As a provision for turning them, the collars 8 are outwardly flanged adjacent to the outer ends of the sockets 3, 4, as indicated at 11 and radial pockets 5 12 are formed in said flanges for engagement by a spanner wrench or the like.

Centrifugal stresses acting upon the blades, in the use of the propeller, are transmitted to the hub through the collars 8 and it is 10 desirable that a considerable area of each collar receive such stresses rather than their inner ends only. Thus, it is preferred to slightly flare the collars 8 from their outer to their inner ends and to correspondingly 15 taper the grooved portions of the blades, gripped by said collars, as Figure 1 clearly shows.

Describing now the provision made for adjusting each propeller blade rotatively in its socket, 13 designates a gauge piece or bar extending upon and around the inner end of the member 4 of each socket, through a suitable arc as for example one hundred and twenty degrees. Preferably the portion of 25 each member 4 seating said bar is raised or embossed slightly as indicated at 14. Said gauge pieces when once located relative to the corresponding sockets 4, are held in the describe dpositions by cap screws 15, a pair 30 of which pass through the longitudinal slots 16 in the end portions of each gauge piece, the latter being thus afforded a limited arcuate travel with respect to said screws when the latter are loosened. Projecting inwardly 35 from said gauge piece, midway of its length, is a key 17 which fits snugly into an opening 18 in the shank 7 thus adapting said gauge piece to accurately indicate the rotative position of the blade. The opening 19 40 of the member 4 through which said key projects is slotted through a sufficient arc to afford the shank 7 (and gauge piece 13) such rotative play as may be required. Upon a lateral face of said gauge piece, a scale 20 is 45 marked and a coacting vernier scale is marked upon the boss 14, as indicated at 21. The cap screws 15 are headed to hold the gauge piece 13 in place when loosened without restraining it from adjustment, and 50 it is preferred to engage the heads of said cap screws by the out-turned ends of a locking strip 22 to prevent turning of said screws.

In the modified construction shown by Fig. 5, a propeller blade shank 23 is rotatively braced by a collar 24, externally threaded to engage the socket 25, this construction differing from that already described only in that the inner face of said collar and the engaged portion of the shank 23 are annularly stepped, as indicated at 26 instead of having the gradual flare of the first described construction. This will transmit centrifugal stresses arising in the shank to the series of annular steps formed in the collar and will 65 exercise a lesser expansive bursting effect

on the collar than will be true of the first described construction.

In use of said construction, the collar 8 will be disposed in the channel 9, embracing the shank 7, and the latter will then be engaged, in approximately its final position 70 with the socket member 3. The socket member 4 will then be applied and the bolts 5 tightened up but not sufficiently to interfere with rotation of the shank 7 or collar 8. 75 The collars 8 may now be turned to adjust the blades outwardly or inwardly, as may be necessary to equalize their effective distance from the propeller axis. In effecting this adjustment, any desired member may be held 80 in fixed relation to the propeller and near the tips of the blades to gauge their relative outward extent.

To assure uniformity of pitch of the blades with regard to the plane of rotation of the 85 propeller, the blades are turned until the same relation is established between the scales 20 and 21 of both blades.

Finally, the bolts 5 are fully tightened, 90 clamping the collars 8 firmly in the sockets 3, 4 and firmly clamping the shanks 7 in said collars.

The construction is one that provides for an accurately balanced initial assembly of a 95 propeller and also permits accurately correct positioning of any blade that may be required to replace one originally provided.

While it will be apparent that the illustrated embodiment of my invention herein disclosed is well calculated to adequately fulfill the objects and advantages primarily stated, it is to be understood that the invention is susceptible to variation, modification and change within the spirit and scope of the 100 subjoined claims.

What I claim is:

1. A propeller comprising a hub member having a radial socket, a propeller blade having a shank rotatively fitted in said socket, a split collar rotative upon said shank and restrained from shifting longitudinally of said shank and screw threaded into said socket whereby the shank is adjustable to and from the axis of the hub member by rotation of said collar, and means for radially contracting 110 said socket about said collar and shank.

2. A propeller blade comprising a hub member having a contractible radial socket internally screw threaded, a propeller blade having a shank rotatively fitted in said socket, a split collar rotative upon said shank contractible to clamp said shank and restrained from longitudinal shifting upon the shank, said collar being externally threaded to engage the threads of said socket whereby to 120 permit radial adjustment of said blade, and means for contracting said socket to rigidly clamp said collar and shank.

3. In a propeller, in combination, a hub member having a radially extending split 130

socket, a propeller blade having a shank receivable in said socket, said shank having a circumferentially extending recess therein, and a split collar rotatably encircling the recessed portion of said shank and maintained 5 against axial movement relative thereto, said collar being received within said socket and having threaded engagement therewith and means to contract the socket.

4. In a propeller, in combination, a hub member having a radially disposed socket, a propeller blade having a shank rotatably received in said socket, the inner end of said shank bearing against the side walls of said socket and said shank being circumferentially recessed outwardly thereof, a split collar encircling said shank and received in said recess against axial displacement with respect thereto, said collar being externally formed for screw threaded engagement with the interior walls of said socket, and means for radially contracting said socket whereby to clamp said collar between said socket and said shank.

5. In a propeller, in combination, a hub member having a radially disposed socket, a propeller blade having a shank rotatably received in said socket, the inner end of said shank bearing against the side walls of said socket and said shank being circumferentially recessed outwardly thereof, a split collar encircling said shank and received against axial displacement in said recess, said collar being externally formed for screw threaded engagement with the interior walls of said socket, and means for radially contracting said socket whereby to clamp said collar between said socket and said shank, and to clamp said shank directly by said collar.

6. A propeller comprising a hub member having a radial contractible socket, a propeller blade having a shank in said socket, a split collar rotatively engaging said shank within the socket and being secured against axial displacement with respect to the shank, said collar and socket having engaging screw threads, and means for contracting the collar into clamping engagement with said shank, the collar opening being flared toward the hub axis and the shank being correspondingly tapered, whereby centrifugal stresses to which the shank is subjected are transmitted to an extended area of the collar.

7. A propeller comprising a hub member having a contractible radial socket, a propeller blade having a shank engaged in said socket and formed with an annular channel within the socket, a segmental collar embracing said shank within said channel and being secured against axial displacement with respect to the shank and contractible to clamp the shank against rotation, said collar and socket having screw-threaded engagement for adjusting the shank to and from the axis 65 of the hub member, and means for contrac-

tively clamping the socket upon said collar and thereby clamping the shank within the collar.

8. A propeller blade comprising a hub member having a radial socket, a propeller 70 blade having a shank engaged in said socket, a collar rotatively engaging the shank and restrained from end-wise travel upon the shank, said collar and socket having screw-threaded engagement to adapt the collar through 75 rotation in the socket to adjust the shank to or from the axis of the hub member, and an element for indicating rotative positions of the shank engaging the latter between said collar and the inner end of the socket and projecting through the socket wall and adapted for a limited rotation in the socket wall.

9. In a propeller, in combination, a hub member provided with a radially extending socket, said socket being diametrically split 80 into two halves one of which is integral with said hub and the other of which is detachably secured to the integrally formed half, a blade having a circumferentially recessed shank received in said socket, and a split collar 85 retained in said recess and threadably engaging the walls of said socket the collar and the shank being secured for relative rotation without axial displacement and means for rigidly clamping the socket, collar and shank 95 together.

10. In a propeller, in combination, a hub member provided with a radially extending socket, said socket being diametrically split 100 into two halves, one of which is integral with said hub and the other of which is detachably secured to the integrally formed half, a blade having a circumferentially recessed shank received in said socket, and a split collar retained in said recess against axial displacement with respect to the shank and threadably engaging the walls of said socket, said detachable half adapted to clamp said collar and shank against axial or radial movement relative to said integral half when secured thereto.

11. In a propeller, in combination, a hub member provided with a radially extending socket, a propeller blade having a shank received in said socket, said shank being provided with a plurality of radially extending axially spaced thrust surfaces, and a split collar surrounding said shank and threadably engaging the interior walls of said socket, the shank and the collar being relatively 115 rotatable with respect to each other without relative axial displacement, the interior walls of said collar being formed with a plurality of surfaces complementary to said thrust surfaces for engagement therewith and means for contracting the socket to clamp the collar.

12. In a propeller, in combination, a hub member provided with a radially extending socket element, a propeller blade having a 130

- shank element rotatably received in said socket element, a split collar interposed between said elements and operatively engaging both, said collar being axially adjustable with respect to the socket to vary the radial position of said shank element in said socket and being rotatable without axial displacement relative to the shank to vary the rotatable relation between said elements, and additional means for contracting said socket element about the first mentioned means and said shank element.
13. A propeller blade having a shank, said shank having a smooth walled annular channel peripherally formed therein, the bottom of said channel tapering from one end thereof to the other end thereof and having abruptly curved end walls forming abutment surfaces.
14. In a propeller, in combination, a hub having a socket, a propeller blade having a shank rotatably received in said socket, means for contracting said socket about said shank to lock it in rotatably adjusted position, said shank having an axially parallel slot in the periphery thereof, said socket having a slot therein transverse to said slot in said shank, an indicating member overlying the margins of said slot in said socket, a pin on said member projecting through said slot in said socket and slidably received in said slot in said shank, and means for securing said member against movement to said socket.
15. In a propeller, in combination, a hub having a socket, a propeller blade having a shank rotatably received in said socket, means for contracting said socket about said shank to lock it in rotatably adjusted position, said shank having an axially parallel slot in the periphery thereof, said socket having a circumferential slot therein, a circumferentially elongated indicating member overlying the margins of said slot in said socket, a pin on said member projecting through said slot in said socket and slidably engaging said slot in said shank, said member having a circumferentially extending slot therein, and clamping means extending through said slot in said member and engaging said socket for locking said member in adjusted position.

JOHN SQUIRES.
